UNITED STATES PATENT OFFICE

158,534

MERCHANDISING DISPLAY CABINET OR SIMILAR ARTICLE

Arthur C. Wesche, Bridgeport, Conn., assignor to General Electric Company, a corporation of
New York

Application December 18, 1948, Serial No. 150,232

Term of patent 14 years

(Cl. D80—11)

To all whom it may concern:

Be it known that I, Arthur C. Wesche, a citizen of the United States, residing at Bridgeport, in the county of Fairfield, State of Connecticut, have invented a new, original, and ornamental Design for a Merchandising Display Cabinet or Similar Article, of which the following is a specification, reference being had to the accompanying drawing, forming a part thereof.

The single figure of the drawing is a perspective view of a merchandising display cabinet or similar article embodying my new design. The opposite end wall of the cabinet is of the same design as the one shown and the rear side of the cabinet is substantially plain.

I claim:

The ornamental design for a merchandising display cabinet or similar article, substantially as shown and described.

ARTHUR C. WESCHE.
